Dec. 658

John C Smith of Philadelphia Pa.
Assignor to
Warrick & Leibrandt of same place
Letters Patent N° 658. Dated July 11th 1854

The schedule referred to in these Letters Patent and making part of the same.

To all whom these presents shall come.

Be it known that I John C Smith of Philadelphia in the County of Philadelphia and State of Pennsylvania, have invented a new and original design for Cook Stove called the "Great Republic". And I do hereby declare

that the following is a full, clear, and exact description of the same; reference being had to the annexed drawings forming part of this specification, in which

Figure 1 is a front elevation of the stove.

Figure 2 a side elevation of the same.

Figure 3 an elevation of the foot.

In the several figures the same letters represent the same part of stove and design. Symmetrical designs have but one half of their details shown.

The side plates A of this stove bear the panels B, C and D, the former raised by the moulding E, and C and D, by the mouldings F and G, the arrangement and composition of which is shown in the sections x x, z z, and y y. The surface of the plate is slightly sunken and surrounded by the waving edge a, while above this edge and running horizontally is the moulding G, which extending around on the front plate forms a cornice to the stove. At the bottom of the plate is the moulding H. The panel B is of the form shown in figure 2 and bears in bas-relief the sweeping foliage C entwined with, and crossed by the twig d, bearing the leaves e, arranged and having the configuration shown in the above mentioned figure. The panel C is ornamented in bas-relief by the foliage f crossed by the twig g, at the extremity of which is the leaf h.

The panel D also bears an ornament of a similar design the foliage is forming a number indicative of the size of the stove, across which runs the leaf stem K. Above the panels B and D is the inscription "Patented 1854. Great Republic," and below the panels B and C "Warnick & Leibrandt. Philadelphia" both in raised capitals and numerals. The arrangement and configuration of the several designs on the sides of the stove are as set forth in figure 2. The front doors M M are raised by a moulding I and bear the ornaments J in bas-relief composed of foliage l and leaf m the arrangement and configuration

3

Des. 658

being as set forth in figure 1. The top plate P has on its edge the moulding u and overhangs the front, sides, and back with the waving edge v arranged and configured as shown in the drawing.

The foot R bears on each side the foliage of sweeping from the bottom and meeting at the swell of the upper portion. In front is the leaf w from which issues two stems s crossing the foliage y and terminating in leaves t, the whole being in bas-relief and having the arrangement and configuration shown in figure 3.

What I claim as new and original and of my own production, is the design, configuration and arrangement of the several ornaments in bas-relief and mouldings as herein described, and represented in the annexed drawing, forming the design of Stove "Great Republic"

In testimony whereof I have hereunto signed my name before two subscribing witnesses
